ROAD-FORMING MACHINE.

1,350,060.

Specification of Letters Patent. Patented Aug. 17, 1920.

Application filed July 12, 1919. Serial No. 310,391.

To all whom it may concern:

Be it known that I, BICK R. BONNEY, a citizen of the United States, residing at Omaha, in the county of Douglas and State of Nebraska, have invented certain new and useful Improvements in Road-Forming Machines, of which the following is a specification.

This invention relates to a road-forming machine of the class used in forming ditches at the sides of the road and moving the ground toward the middle of the road from the ditches, and forming a road surface convexed in cross-section. The invention has for its object, broadly, to provide such a construction that a limited power, comparatively, will be required for moving the ground surface, and includes certain features relating to convenience in control and operation, and certain adjustable features found to be of advantage, all as hereinafter fully described and claimed, and as illustrated in the accompanying drawing, wherein.—

Figure 1 is a plan view of a road-forming machine embodying the invention. Fig. 2 is a view showing the end and rear part of the machine, said view being taken parallel with the operating shaft and longitudinal axis of the traction wheel. Fig. 3 is a broken away detail showing an end view of a pair of connected scraper-blades. Figs. 4 and 5 illustrate journaled bearings of the axle in a part of the oscillating machine frame, Fig. 4 showing the axle in transverse section, and Fig. 5 showing the frame in section. Fig. 6 is an enlarged detail, partly in section, relating to Fig. 1 to clearly show the use of a universal joint in connection with the mounting, on the axle, of a pair of blade-arms, the axle being in section. Fig. 7 is a plan view of the parts shown in Fig. 6. Figs. 8 and 9 are enlarged details, partly broken away, illustrating means for the control of the movements of the oscillating frame. Fig. 8 shows the position of parts for maintaining the oscillating-frame in a horizontal position. Fig. 9 shows the position of parts when the front of the oscillating frame has been swung downwardly for elevating the blades, to permit dumping.

Referring now to the drawing for a more particular description, I provide a frame 1 of elongated form, adapted to have a swinging movement forwardly and rearwardly

from a non-revoluble axle 2, said axle being provided with an inclined part *a* outwardly of one end of the frame for a mounting thereon of a traction wheel 3. Numeral 4 indicates a caster wheel, its pintle *b* being disposed midway between the front and rear parts of the frame 1, adjacent to that end of said frame opposite to the wheel 3. Numerals 5 indicate cross-pieces for reinforcing the frame thus described. 60 65

I provide an over-frame consisting of a tongue 6 disposed substantially at right-angles to the inclined part *a* of the axle, said tongue, as best shown in Fig. 1, extending rearwardly to overhang the axle and a part of the frame 1, for use in mounting certain operating parts thereon, said member 6 being provided with a brace, preferably of V-shape, its arms *c* and *d* being rigidly mounted upon the axle, the front 70 75 end of the tongue having a vertical part *e* provided with apertures *f* for use when connecting the device with a tractor or similar object for moving the device forwardly.

By referring to Fig. 1 it will be seen that 80 the connections for the front ends of the brace-arms *c* and *d* with the tongue are adjacent to the front end of the latter, and since the rear ends of said arms and the tongue are rigidly mounted upon the axle 85 the frame 1 may have a limited swinging movement relative to the overframe, the frame 1 and members 5 having journaled bearings upon the axle. Numeral 7 indicates a link or bar suitably connected with 90 the axle outwardly of the frame 1, for the support of a platform 8.

At 9 are indicated a plurality of transversely curved blades, and at 10 is indicated a comparatively short blade which is also 95 transversely curved, and for convenience, is identified as a ditch-blade, these being disposed approximately in line, rearwardly of the frame 1, the "off" end of each blade 9 being disposed rearwardly of the "near" 100 end of a blade adjacent thereto, each blade 9 and the blade 10 being provided with a pair of convergently disposed tongue-arms 11, the L-shaped bar 12 (Figs. 6, 7,) which connects each pair of arms 11, at their junction, being received by a swivel member 13 which is mounted in a clevis 14, the latter being rigidly mounted upon the axle; and it will be understood that, on account of this construction, both longitudinal and trans- 105 110

verse swinging movements will be permitted for said blades. Also since the L-shaped bars are provided with apertures g at longitudinal intervals, the front ends of the 5 tongue-arms 11 for the blades 9 and 10 may be elevated or lowered for changing the pitch or inclination of said blades for suitably engaging the ground, said tongue-arms 11 at their rear ends being rigidly mounted 10 upon the blades.

The machine when moving forwardly is adapted to form a road bed having a convexed surface in cross-section, the blades engaging in the ground and causing the 15 loosened soil to be conducted toward the middle of the road bed, means to be employed, and to be described, under control of a driver or operator, for changing the inclination, longitudinally, of the blade 10, 20 so that it will form a ditch. Numeral 15 indicates a cutter-disk disposed forwardly of the outer end of the blade 10 for cutting the ground or sod in the formation of a gutter or ditch, said disk having a frame 25 or tongue 16 of sufficient weight to cause the disk to suitably enter the ground, said tongue being pivotally connected with the frame 1, as best shown in Fig. 2.

In order that the blades 9 may be adjusted 30 as to height to form a road bed having a convexed surface in cross-section, pull-rods 17 are employed for a connection with certain bell-crank 18, the latter being mounted upon the rear part of the frame 1, and any 35 suitable connection may be made of the bell-crank 18 with said blades 9, said connection in the present instance being chains 19, the lower ends of each chain being mounted upon a coupling-pin 20 which connects the 40 adjacent ends of said blades as best shown in Fig. 3; and by means of hand-levers 21 and the conventional toothed sectors which are mounted upon the platform 8, an operator may elevate or lower said blades 9 45 for engaging the ground to form the required curvature of a road bed.

The blade 10 may also be elevated or lowered by similar means to that last described, toothed sectors 22 being mounted upon the 50 platform 8 and used in connection with hand-levers 23, rigid pull-and-push rods 24 being employed and connected with bell-crank 18', and rigid links 25 and 25' also being employed and connected with said 55 bell-crank, the link 25 being connected with the outer end of the blade 10, and the link 25' being connected with that end of the blade 9 adjacent to said blade 10, whereby the outer end of said blade 10 may be elevated or lowered independently of its inner 60 end, said inner end of the blade 10 being pivotally connected, as indicated at h with said blade 9, the advantage to be derived by this construction being that an operator, 65 by use of hand-levers 23, may conveniently

maintain the blade 10 with its outer end somewhat lower than the other blades, to form a ditch, the end of the blade adjacent thereto being under similar control by means of the link 25' to cause it to be lowered 70 for the formation of the ditch, in conjunction with the curved surface of the road bed.

It will be appreciated that the stresses directed to the frame and axle occasioned, 75 during operation, by the resistance of the blades while engaging in the ground, will be sustained to advantage, since, longitudinally considered, the frame 1, and axle and the blades, are disposed inclinedly with reference to the tongue and wheel 3.

It will be understood that the accumulations of earth during operation, will be carried forwardly by the blades 9 and 10, and that the blades, on account of their form, 85 will contain or hold these accumulations, and therefore an upward movement of the blades for dumping, may require considerable force, and that if levers alone were depended upon for this purpose, operation 90 would be attended with some difficulty; and therefore I provide means, movable by the wheel 3, for causing a swinging movement upon the axle of the frame 1, for elevating the blades, said means being best shown in 95 Figs. 8 and 9.

Numeral 26 indicates an operating-shaft in suitable bearings, said shaft being disposed approximately at right-angles to the tongue 6 and parallel with the extension a of the axle 2, one of its ends having a drum k mounted thereon as an idler, its opposite end being provided with a sprocket wheel m , said shaft being revoluble by means of a sprocket-chain m' in engagement with a sprocket-wheel n which is provided for the wheel 3.

In order that the drum may be rotated whenever desired, a conventional clutch r is splined upon the shaft 26, and may be 110 moved into engagement with the drum by means of the arm s of a bell-crank 27 which is mounted upon a bracket 28, the latter being secured to the tongue 6, said bell-crank 27 being movable by means of a pull-and-push rod 29, under control of a hand-lever 30 which, as best shown in Figs. 8 and 9, is provided with a toothed sector x and, in part, is controlled by a spring x' and by a conventional pawl, as shown. 115

The lever 30 is also provided with a rod 31 adapted to control the movements of a pawl-member 32, the latter being slidably mounted upon the flange 33 of the tongue. 120

Numeral 34 indicates an operating-bar disposed parallel with and having a pivotal mounting for one of its ends upon the tongue, its opposite end being provided with a pulley 35. At 36 is indicated a spacing-bar, its upper end being pivotally mounted 125 130

- upon the bar 36 between the ends thereof, its lower end being pivotally mounted upon a bracket 37 which is disposed below the tongue and is secured upon the front part 5 of the frame 1. Mounted upon the tongue is a second pulley 38, and at 39 is indicated a cable having its respective ends secured to the drum and to the tongue, said cable being in engagement with the pulleys 35 and 38.
- 10 The bar 36 is provided with notches or recesses *t* and *v*, and the normal position of parts are as shown in Figs. 2 and 8, the operating-bar projecting above the tongue, the clutch *r* being disengaged from the drum
- 15 and the frame 1 being disposed in a horizontal position, the parts being held in the positions mentioned on account of engagement of the pawl-member 32 within the recess *v* of the bar 36.
- 20 When the operation of "dumping" is required, the operator, while the machine is moving forwardly, causes the lever 30 to swing forwardly, which causes a swinging movement of the bell-crank 27 for moving the clutch *r* into engagement with the drum to cause a rotation thereof, said forward swinging movement of the lever 30 also causing the pawl 32 to be withdrawn from the recess *v* to permit the levers 34 and 36 30 to move downwardly.

The downward movement of levers 34 and 36 operate to cause the front part of the frame 1 to swing downwardly, the rear part of said frame 1, together with the blades 9 and 10 being elevated, the elevation of said blades operating to release the accumulations of earth held by said blades.

Since the machine is moving forwardly during the operation last described, the release of the accumulated earth from the blades will be gradual, and will be spread to advantage uniformly upon the surface of the road-bed.

Numeral 40 (Figs. 8, 9,) indicates a ball 45 or detent which is secured to the cable 39, and when said cable is wound upon the drum by the means described, said detent will engage the arm *w* of the bell-crank 27 and will cause it to swing, its swinging 50 movement causing a movement of the clutch, and causing a release of said clutch from the drum, so that a further revoluble movement of the drum will be prevented; and the parts are so arranged and proportioned 55 that the pawl 32 will enter the recess *t* as soon as the clutch is moved by the bell-crank 27, this being when the revoluble movement of the drum ceases.

Since the blades 9 and 10, during the forward movement of the machine will be disposed at an angle to the line of travel, the loosened earth will be moved, to a greater or lesser extent, toward the medial line of the road-bed, and weeds, grass, chunks of 65 earth and trash will be conducted readily in

the same direction, and therefore a spreading device is provided consisting of a rake-member 40', preferably having curved tines *z* mounted in an arm 41, said arm being pivotally mounted, as indicated at 42, upon the outer end of a blade 9 to be disposed outwardly and rearwardly of the traction wheel 3 and substantially parallel with the axle-extension *a*, a holder 43 being provided and connected with the axle-extension *a* and the outer end of said arm, the function to be discharged by said member 40' being to cause the material mentioned to become spread upon the surface of the road-bed.

While I have described construction in detail, it will be understood that changes may be made in form, size, proportion and minor details, as may be found to be of advantage, said changes to be determined by the scope of the invention, as claimed.

What I claim as my invention and desire to secure by Letters Patent is,—

1. In a road-forming machine, an axle having an inclinedly disposed part, a frame provided with a caster-wheel and journaled on the axle, a vehicle-wheel journaled on the inclinedly disposed part of the axle, a second frame rigidly mounted on the axle and disposed above the first named frame, scraper-blades connected with the first 95 named frame and also connected with the axle, an operating-shaft revoluble by the revoluble movement of the vehicle wheel, a drum, an operating-bar pivotally mounted on the second frame and provided with a 100 pulley, a cable connected with the drum and second frame and engaging said pulley, a spacing-bar connected with the first named frame and said operating-bar, and a clutch movable for communicating revoluble movements of the operating shaft to the drum.

2. In a road-forming machine, an axle having an inclinedly disposed part, a frame provided with a caster-wheel and journaled on the axle, bell-cranks mounted on the 110 frame, a vehicle-wheel disposed outwardly of the frame and journaled on the inclinedly disposed part of the axle, a second frame rigidly mounted upon the axle and disposed above the first named frame, scraper-blades 115 disposed in a plane below the first named frame and connected with the bell-cranks and also connected with the axle, a plurality of hand-levers, pull-rods connecting the bell-cranks with said hand-levers, means 120 for adjusting the hand-levers for maintaining the scraper-blades at selected distances from the first named frame, an operating-shaft revoluble by the revoluble movement of the vehicle wheel, a drum, an operating-bar mounted on the second frame and provided with a pulley, a cable connected with the drum and second frame and engaging said pulley, a spacing-bar connected with the first named frame and the operating- 130

bar, and a clutch movable for imparting revoluble movements of the operating shaft to the drum.

3. In a road-forming machine, an axle, a vehicle wheel journaled on the axle, a frame provided with a caster-wheel and journaled on the axle, a second frame rigidly mounted on the axle and disposed above the first named frame, tongue-arms having their inner ends connected with the axle to permit vertical adjustments thereon and having their opposite ends extending rearwardly of the first named frame, a plurality of scraper-blades each being rigidly connected with a pair of tongue-arms, an operating-shaft revoluble by the revoluble movement of said vehicle wheel, a drum, an operating-bar pivotally mounted on the second frame and provided with a pulley, a cable connected with the drum and second frame and engaging said pulley, a spacing-bar connected with the operating-bar and first named frame, and a clutch movable for communicating revoluble movements of the shaft to said drum.

4. In a road-forming machine, an axle, a vehicle-wheel journaled on the axle, a frame journaled on the axle and provided with a caster-wheel, bell-cranks mounted on the frame, a second frame above the first named frame and rigidly mounted upon the axle, scraper-blades disposed in a plane below the first named frame and adjustably connected with the axle, links connecting the scraper-blades with the bell-cranks, a plurality of hand-levers, pull-and-push rods connecting the bell-cranks with the hand-levers, means for adjusting the hand-levers for maintaining the scraper-blades at selected distances from the first named frame, an operating-shaft revoluble by the revoluble movement of the vehicle-wheel, a drum, an operating-bar mounted on the second

frame and provided with a pulley, a cable connected with the drum and second frame and engaging said pulley, a spacing-bar connected with the operating-bar and first named frame, and a clutch movable for imparting a revoluble movement of the shaft to the drum.

5. In a road-forming machine, the combination with the axle of a vehicle, a frame journaled on the axle, a tongue above and rigidly connected with the axle, a plurality of bell-cranks on the frame, tongue-arms connected with and arranged for vertical adjustments on the axle, scraper-blades mounted on the tongue-arms, links connecting the scraper-blades with the bell-cranks, means for actuating the bell-cranks for moving the scraper-blades, and means to cause a swinging movement of the frame for elevating said scraper-blades.

6. In a road-forming machine, the combination with the axle of a vehicle, of a frame journaled on the axle, a tongue above and rigidly connected with the axle, a plurality of bell-cranks on the frame, tongue-arms connected with and arranged for vertical adjustments on the axle, scraper-blades mounted on the tongue-arms, links connecting the scraper-blades with the bell-cranks, a plurality of push-and-pull rods each being connected with an end of a scraper-blade, each rod being movable for moving a link for moving an end of a scraper-blade, and means to cause a swinging movement of the frame for simultaneously lowering said scraper-blades.

In testimony whereof I have affixed my signature in presence of two witnesses.

BICK R. BONNEY.
